Charles L. Wright

UNITED STATES PATENT OFFICE.

ABRAHAM WEISS, OF NEW YORK, N. Y.

SUCTION GRINDING AND POLISHING MACHINE.

1,408,851.

Specification of Letters Patent.

Patented Mar. 7, 1922.

Application filed March 8, 1920. Serial No. 364,132.

To all whom it may concern:

Be it known that I, ABRAHAM WEISS, a citizen of the United States, and a resident of New York, in the county and State of New York, have invented certain new and useful Improvements in Suction Grinding and Polishing Machines, of which the following is a specification.

This invention has for one of its objects 10 to provide a perforate abrading surface for finishing articles particularly the soles and heels of leather shoes by grinding the same smooth and free from roughness or irregularities, the surface taking the form of a roll, 15 or wheel as may be most conveniently used.

Another object is to provide a perforate driver for the abrading element used, the driver being of hollow construction and engaged with a suction device whereby the 20 dust and particles removed from the article are drawn in and carried away, relieving the air and surroundings from unhealthy and filthy conditions usually attendant upon such operations.

25 These objects are attained by the novel construction and combination of parts hereinafter described and shown in the accompanying drawings, forming a material part of this disclosure, and in which:—

30 Figure 1 is a front elevational view of an abrasive roll and connections made in accordance with the invention.

Figure 2 is a longitudinal sectional view taken through the center of the same.

35 Figure 3 is a transverse sectional view taken through the roll, bench and guard.

Figure 4 is a fragmentary plan view of the roll covering.

Referring to Figures 1 to 3 of the drawings in detail, the numeral 50 designates a 40 hollow shaft adapted for rotation in bearings (not shown) and provided at one end with a conical enlargement 51 rotatable in a sleeve 52 in which is threaded an adapter 53 having a stem 54 used to connect a flexible tube 55 leading to a suction device in which a partial vacuum is constantly maintained.

Formed in the walls of the hollow shaft 50 45 are a plurality of elongated open slots 58 arranged in spaced relation and extending longitudinally at one or more fixed points.

A drum or hollow roll 60 having flanged sides 61, is held to the shaft by hubs 62 55 through which pass cotter pins 63 or like fastenings, the same passing entirely

through the shaft and spread at their lower ends as indicated, the drum being so located on the shaft as to enclose the slots 58.

A plurality of staggered or offset openings 64 are formed through the peripheral wall of the drum, which also contains a longitudinal undercut slot 65 to receive the abutting ends of a strip of abrasive material, as sand-paper, emery-cloth or the like 66 65 wrapped tightly and smoothly around the drum, the ends being secured by a wedge 67 or like fastener.

This abrasive strip 66 contains a plurality of openings 68, which are adjusted and 70 caused to register with the openings 64, thus providing a plurality of clear unobstructed passages leading to the interior of the drum and from thence through the slots 58 to the interior of the hollow shaft so that all dust 75 and loose small particles are removed as fast as made.

A bench or support 70 is indicated in Fig. 3, the same supporting a curved guard 71 disposed partially over the roll or drum 80 while at the front is a fixed work support 72 for convenience in presenting the articles to be operated upon to the face of the revolving drum.

Having thus described my invention, explained its manner of operation and construction, what I claim as new and desire to secure by Letters Patent, is:—

1. An abrading device comprising in combination, a hollow shaft engaged with a 90 suction means, a drum fixed on said shaft communicating with the interior, said drum having a perforate periphery containing a longitudinal slot, a flat strip of abrasive material containing perforations registerable with the perforations in said drum, and means for securing the ends of said strip within the slot contained in the drum. 95

2. An abrading device comprising in combination, a hollow shaft engaged with a 100 suction means, said shaft having openings through its walls, a perforate drum removably secured to said shaft enclosing the mentioned openings, a perforate sheet of abrasive material covering said drum, and 105 means for detachably engaging said covering at its ends to said drum.

3. An abrading device comprising in combination, a hollow shaft rotatably mounted, a flexible tube engaged at one end 110 of said shaft leading to a suction chamber, said shaft containing a plurality of grouped

openings, a drum having a perforate periphery and containing an undercut longitudinal slot, means for removably engaging said drum to said shaft to cover the mentioned openings, a perforate strip of abrasive material removably enveloping said drum, the perforations in said strip and drum being in register, and a key for securing the ends of said strip in the slot of said drum.

4. An abrading device comprising a per-

forated drum, suction connection with said drum, a band of abrasive material containing perforations, means for detachably securing said band to the drum hubs at the ends of said drum, a hollow shaft communicating with the interior of the drum, and means for removably engaging said drum to said shaft.

In testimony whereof I have signed my name to this specification.

ABRAHAM WEISS.
